RINSE WRINGER CONSTRUCTION

Orin N. Cooper, Garwin, Iowa

Application May 6, 1955, Serial No. 506,515

6 Claims. (Cl. 68—22)

This invention relates to a rinse wringer construction and is more specifically directed to a new and novel design of drain board means constructed and arranged to channel and divert excess rinse water to a drain area for discharge.

The present wringer construction generally incorporates and embodies rinsing structure disposed adjacent the clothes receiving side of the wringer with a downwardly directed rinse water spray being associated with the wringer roll pressure release bar and an upwardly directed rinse water spray being associated with the wringer drain board at the clothes feed side of the wringer, all as more completely set forth and described in my Patent No. 2,689,471, issued September 21, 1954. The invention also comprises an improvement in the clothes rinsing means for wringers as set forth in my co-pending application Serial No. 259,741, filed on December 4, 1951, now Patent No. 2,748,586, dated June 5, 1956.

When rinse water from an external source is applied to garments as they enter the wringer rolls such additional and excess water must be disposed of and kept from draining back into the clothes washing tub. Some diversion is not entirely objectionable, but since the rinse water is normally cold water this water would lower the tub water temperature. At the same time the tub water level will be raised above the normal high water level suited for the washing operation as recommended by the washing machine manufacturer.

One of the objects of this invention is to provide a drain board for a wringer having a predetermined configuration and contour to divert wringer rinse water toward and into a rinse water drain area and away from flowage into the tub of the washing machine.

Another object of the present invention is to provide a drain board for use with a rinse wringer arrangement and wherein said drain board includes a forward raised ridge or weir portion disposed to terminate in vertical spaced relation above a horizontal plane coincident with the line of tangency of the wringer rolls. With this provision the garments are held in suspended relation above the drain surface of the drain board stretching between the raised ridge and the wringer rolls.

A still further object is to position a rinse water discharge area as a part of the drain board that is located toward the wringer rolls and well below both the forward raised edge of the board and the level of the line of tangency of the wringer rolls.

As another object of the invention the raised ridge on the drain board terminates in a fairly sharp edge to provide a squeegee or wash water releasing action to return a considerable amount of the wash water in the clothes into the tub as the clothes are passing over the drain board edge and on the way to the wringer rolls. Thus less wash water is carried over with the clothing during the wringer function and better rinsing results.

Other objects have to do with such factors as the use of a reverse slope on the drain board to divert water

2

toward the wringer rolls toward drain means and this slope also prevents water from collecting or standing upon any portion of the board drain surfaces; the provision of a modified raised edge on the forward portion 5 of the drain board to provide a squeegee edge arranged substantially at right angles to the lifting pull of the garments going to the wringer; and also the provision of undercut portions at the drain board raised edge and on the wringer roll side thereof to further counteract possible overflow or return of garment water and rinse water back into the tub.

Certain other objects relating to novel features of the present invention will hereinafter become apparent from the following detailed description having reference to 15 the accompanying drawings illustrating the invention and forming a part of this specification.

In the drawings:

Fig. 1 is a side elevation view of the upper part of a 20 washing machine having a wringer embodying the present invention, the wringer being shown in operative position and as it appears from the clothes receiving side thereof;

Fig. 2 is a fragmentary vertical cross sectional view 25 taken transversely through the wringer and wringer rolls and substantially as viewed along the plane of the line 2—2 in Fig. 1;

Fig. 3 is a plan view of the drain board of the present 30 invention as it appears when removed from the wringer frame; and

Fig. 4 is a fragmentary sectional view of a forward 35 section of the drain board construction of this invention, but illustrating a modified design of a raised forward edge or weir.

Referring now to Fig. 1, the washing machine 1 has 35 a tub 2 including a connected wringer post 3 to carry the base fixture 4 of a wringer 5 that incorporates the drain board 6 of the present improved design. The wringer 5 carries upper and lower wringer rolls 7 and 8 respectively suitably mounted in the wringer frame 9, with the 40 operating handle 10 being provided to control the operation of the wringer in the conventional manner.

The wringer also carries suitable pressure release bars 45 11 and 12, the bar 11 being hollow as at 13 to provide a conduit along its length and also is provided with rows of small ports or openings 14 and 15 along the lower edge of the bar to establish a clean water spray source above the clothes path to rinse the garments as they are fed into the wringer rolls 7 and 8.

The drain board 6 comprises a vertical wall or apron 50 16 contiguously blending into end walls or aprons 17 and 18 with the apron 16 terminating with a raised forwardly disposed weir or ridge 19 that leads between the upwardly positioned and upsloping end barriers 20 and 21 of the drain board 6. The balance of the drain board 6 55 includes a trough 22 defined by the upper surface of the wall or baffle 23 and the inner surface of the connecting wall structures comprising the weir 19 and barriers 20 and 21.

The wringer side or face 24 of the drain board 6 has 60 suitable extensions 25 and 26 adapted for securement with structural portions of the wringer frame 9 to securely hold and mount the drain board with its face 24 flush against the adjacent wringer face 27.

The drain board 6 is also provided with a depending 65 rearwardly sloping wall 28 including a heavier body section 29 formed between wall 23 and wall 28 that is hollowed out at 30 to provide a rinse water conduit. Rows of rinse water discharge ports 31 and 32 communicate with conduit 30 and these ports are positioned to direct a 70 rinse spray against the underside of a garment such as 33 when the latter is fed through the wringer rolls 7 and 8. Rinse water may be supplied to the pressure release bar

rinse water conduit 13 and to the drain board rinse water conduit 30 through a flexible hose 34 connected with a suitable cold water supply and being joined with a nipple 35 secured to the inlet leg 36 of a valve 37 that carries a valve wheel 38 to open or close the valve 37. Branch outlet nipples 39 and 40 each have flexible hose sections 41 and 42 respectively which connect with inlet nipples 43 and 44 carried by the pressure release bar 11 and drain board 6 to communicate with conduits 13 and 30 respectively. Thus rinse water can be selectively turned on or off as required and the quantity of water may also be regulated for different conditions of operation or as may be desired by the operator.

A drain pan 45 is mounted in the wringer frame 9 and is fitted to the cavity of the wringer beneath the wringer rolls 7 and 8. The pan has a discharge nipple 46 to which a drain hose 47 is secured, the hose 47 providing suitable means for the disposal of the wringer water to a drain or to a pump or pump connection if that is feasible and desirable.

The forward top edge of the pan 45 is provided with an offset flange or rim 48 shaped to receive the depending lip 49 that is part of the structure of the wall 28 of the drain board 6. The rear top edge of the pan 45 also has an offset flange or rim 50 to accommodate the depending lip 51 that is a part of the depending wall 52 of the rear or clothes discharge board 53 that is secured to the rear face or side 54 of the wringer frame 9. The rear discharge board presents the garment guiding trough 55 as outlined by the contour and shape of the wall 56 and the drop-off apron 57.

Referring back to Fig. 2, it should be noted that the clothing is fed to the wringer rolls 7 and 8 along a down slope and this is emphasized by the general angularity of the garment 33 and also by the slope of the dot and dash line 58. This arrangement, therefore, causes rinse water and extracted water to flow over the garment in the general direction of the wringer rolls and about the garment to drain off of the wall 23 and out of the trough 22 over the surface of wall 28 and into the drain pan 45. Simultaneously, the sharp corner 59 on the top edge of the weir 19 functions to extract a good portion of wash water from the garment and which water drains back into the tube 2.

The trough wall 23 slopes down as shown in Fig. 2, and from a level about coincident with the dot and dash line 60, which indicates a horizontal plane coincident with the tangency of the rolls, and to a level where the rinse ports 31 and 32 are located. The object is to keep the garments from riding on the trough surface to promote free uninterrupted flow of extracted and rinse water and to prevent muffling or valving of the rinse water ports 31 and 32 which action would interfere with the desirable and efficient garment penetration of the rinse water streams or sprays.

In Fig. 4, a modified construction of drain board 6a incorporates a different form of weir structure 61 wherein the apron 16a terminates with a horizontally disposed wash water extracting edge 62 under a generally curved garment guiding ridge or crown 63. The trough side of the crown 63 is undercut at 64 to provide a water return well or deflecting means that can be extended about the entire trough area of the drain board and up to the wringer frame face 27. One or more notches 65 may be provided in the long direction of the crown as a further means of retaining and redirecting some of the wash water from a garment back into the tub.

The foregoing description and disclosures relate to preferred and modified forms of the invention. However, certain changes in the combination of the elements and in the individual elements per se are contemplated without departing from the fundamental concept of the invention. Such modifications shall, however, be governed by the breadth and scope of the language set forth in the appended claims.

What I claim is:

1. In a wringer having clothes rinsing spray means for the clothes and a drain pan arrangement under the wringer rolls to collect and to carry away wringer extracted and rinse spray water from clothes passing through said wringer, the improvement consisting of wringer rolls positioned over said drain pan and a water collecting drain board at the clothes entrance side of the rolls, said drain board comprising a trough providing a depending front wall spaced from the rolls and over which clothing may be drawn and guided by the rolls, said trough having an inclined bottom therein leading from said depending front wall downwardly to said rolls for connection with said drain pan, and an upright transverse ridge formed upon said trough bottom and disposed in contiguous relation with respect to said depending trough wall, and upsloping side barriers connected with said ridge to confine the water flow to the drain pan width and wringer roll area, said transverse ridge terminating at a given elevation spaced upwardly from the wringer roll water extraction area to counteract overflow of the trough collected water out of the trough.

2. In a wringer of the character defined in claim 1 wherein said trough bottom downslope originates in the general horizontal plane of the tangency of the rolls and said transverse ridge terminates considerably upwardly with respect to the point of tangency of said wringer rolls.

3. In an over the tub wringer having water spray means for rinsing clothes that are directed through said wringer, said wringer including a pair of horizontally disposed wringer rolls, a water collecting drain structure disposed beneath the wringer rolls to provide water diversion means to conduct rinse spray water and wringer expressed wash water away from the tub; the improvement consisting of drain board means positioned laterally outwardly adjacent the clothes entry side of said wringer rolls, said drain board means comprising a trough having a bottom inclined downwardly and inwardly toward said wringer rolls and presenting a water discharging edge communicating with said water collecting drain structure, said trough including an upstanding weir disposed in the path of the clothes and forming a part of the elevated portion of said inclined trough bottom, said weir terminating in a sharp ridge above said trough bottom and being spaced outwardly from said wringer rolls to provide an abrupt direction changing means ahead of the tangency of said wringer rolls to cause partial wash water extraction from said clothes as they are drawn over said weir ridge toward the tangency point of said wringer rolls through the water spray clothes rinsing means.

4. In the wringer combination set forth and defined in claim 3, wherein said weir ridge terminates at an elevation spaced upwardly from the level of the tangency of said wringer rolls whereby to angle the clothes passing over said weir downwardly and inwardly in the direction of said wringer rolls to cause said rinse and expressed water said wringer rolls to cause said rinse and expressed water to follow the clothing in the same general direction as the inclination of said trough bottom.

5. In a wringer having generally horizontally disposed and vertically aligned rolls with spray means to direct a rinsing spray downwardly on clothes entering the rolls and a drain pan under the rolls to collect and carry away wringer extracted and rinse spray water, the improvement comprising a drain board ahead of the rolls and having a drain surface wall inclined downwardly and inwardly to the drain pan below the rolls, said wall having rinse water spray means to direct a spray upwardly against the underside of clothes entering between said rolls, and an upstanding weir at the outer edge of said wall providing an edge which is angular in cross section and extending well above the plane of tangency of the rolls to act in conjunction with the bight of the rolls and support the clothes in a downwardly sloping path to the bight of the rolls and out of contact with said wall and

its spray means whereby said downwardly directed spray tends to flow downwardly over said clothes towards said rolls.

6. The structure set forth in claim 5, characterized by the weir having a stepped ridge formation at the top to cause partial extraction of wash water from the clothes as the clothes abruptly change direction in passing over said weir.
